UNITED STATES PATENT OFFICE.

IVER JOHNSON, OF TACOMA, WASHINGTON.

COMBINED WINDOW LIFT AND LOCK.

No. 925,914.

Specification of Letters Patent.

Patented June 22, 1909.

Application filed December 14, 1906. Serial No. 347,831.

To all whom it may concern:

Be it known that I, IVER JOHNSON, a citizen of the United States, residing at Tacoma, county of Pierce, State of Washington, have 5 invented certain new and useful Improvements in Combined Window Lifts and Locks, of which the following is a full, clear, and exact description, such as will enable others skilled in the art to which it appertains to make and use the same.

This invention relates to sash-lifts and locks; and one of the objects is to provide means whereby the sashes may be automatically raised or lowered or partially raised or 15 lowered simultaneously or independently of each other.

A further object of the invention is to provide an automatic locking and unlocking device, whereby the sashes may be locked or 20 unlocked in their respective positions, and a manually controlled attachment to operate said locking device adapted for use in case of high windows.

With these and other objects in view the 25 invention consists in the combination and arrangement of parts, as will be hereinafter described, shown in the accompanying drawings, and particularly pointed out in the appended claims; it being understood that minor changes in the detail construction may be 30 made without departing from the spirit of the invention.

In the drawings, Figure 1 is a front view of the inside of a window frame and sashes showing the invention as applied thereto. Fig. 2 is a vertical transverse sectional view thereof showing the relation of the parts of the invention. Fig. 3 is a front view of one 35 of the sashes showing a rack bar attached to each side thereof. Fig. 4 is a side view of one of the rack bars. Fig. 5 is a horizontal sectional view of the frame and sash illustrating the positions of the shafts and spur wheels. Fig. 6 is a bottom plan view of the 40 combined lever, pawl and pulley. Fig. 7 is a side view thereof. Fig. 8 is an elevation of one of the shafts and the spur wheel and drum thereon. Fig. 9 is a side view of one 45 of the spur wheels. Fig. 10 is a fragmentary view of the window frame showing the positioning of one of the shaft supporting plates. Fig. 11 is an elevation of the spring for holding 50 the pawl lever in locking engagement with the spur wheel. Fig. 12 is a vertical

sectional view of the sashes showing the 55 shafts in their relative positions.

Similar reference characters designate corresponding parts throughout the several views of the drawings, referring to which—

A is the window frame with sashes b therein. Arranged at each side of the sashes b are rack bars c, adapted to engage annular series of notches d' on horizontal shafts d for raising or lowering the sashes b. The operating mechanism comprises two of the horizontal 60 shafts d, or one for each sash used, supported in plates k arranged on the inner sides of the frame A and at the meeting rails of the sashes b, one of the shafts d being arranged between the meeting rails of the sashes b, and 65 the other in front of the lower sash, the inner shaft operating the upper sash and the outer shaft the lower sash. On one end of each of the shafts d is mounted a combined spur wheel and drum e, said spur-wheels and 70 drums being positioned within the frame A, between and in alignment with upper and lower guide pulleys a and a'. The guide pulleys a and a' are set in apertures formed in the inner casing of the frame A, the upper 75 guide pulley a being above and adjacent to the drum and spur-wheel e, the lower guide pulley a' being at any desired distance below 80 said spur-wheel.

Interposed between the drum and spur-wheel e and the upper guide pulley a, is a pawl lever f, one end of which is pivoted within the casing and its free end projects through the inner casing of the frame A, for the purpose hereinafter described. On the 85 under side of the pawl lever f is a locking lug f' adapted to engage and lock the spur-wheel e against rotation. Mounted on one side of and adjacent to the free end of the pawl lever f is a tension pulley j, and to normally hold the pawl lever f into locking engagement with the spur-wheel e, I provide a 90 spring g.

A pull cable, cord or chain i, passes over the guide pulleys a and a', and in front of the 100 tension pulley j, said cord also passing around the drum of the spur-wheel e, and said pulley j bears against the cord i to tension the same under the influence of the spring g. I further provide an auxiliary operating device comprising a rod h having an outturned angular member h', the member 105 h' projecting through the casing A, and the

same may be operated by either hand or other means. The upper end of rod *h* is attached to the pawl lever *f*, whereby to release the pawl lever *f* from engagement with the spur-wheel *e*, and is employed when my device is applied to high windows, so that the same may be readily operated when the lever *f* cannot be conveniently reached.

The operation is as follows: When it is desired to raise or lower the windows, the cord *i* is first pulled outward, which, causing tension on the cord, will elevate the tension pulley *j*, and this carries the pawl lever *f* upward, releasing the locking lug *f'* from the spur-wheel *e* so that the drum and spur-wheel are free to rotate. By now pulling the cord either upwardly or downwardly the drum and spur-wheel *e* are caused to rotate, thereby imparting motion to the shaft *d*, and by the notches *d'* of shaft *d* being engaged by the rack bars *c* of the sashes *b*, the sashes may be raised or lowered as desired.

To manipulate windows that are high and difficult to reach, the operator has only to raise either the free end of pawl lever *f* or the angular member *h'* of the operating rod *h*.

Having thus described the invention, what is claimed as new, and desired to be secured by Letters Patent, is:

1. In a device of the class described, a shaft having an annular series of notches, a window sash, a rack bar carried by said sash and engaging the notches of said shaft, means for locking said shaft against movement, and an operating cable for releasing said locking means.

2. In a device of the class described, a shaft having an annular series of notches, a window sash, a rack bar carried by said sash and engaging the notches of said shaft, means for locking said shaft against movement, an operating cable for releasing said locking means, and a connection between said cable and said shaft whereby the latter is operated by said cable.

3. In a device of the class described, a shaft, a gear carried thereby, a window sash, a rack carried by said sash and in mesh with said shaft, whereby said shaft is adapted to operate said sash, means coöoperating with said gear for locking said shaft against movement, and an operating cable for releasing said locking means.

4. In a device of the class described, a shaft, a window sash connected to said shaft for operation thereby, a pawl with locking means to prevent movement of the shaft, a drum associated with said shaft, and an operating cable wound upon said drum and asso-

ciated with said pawl for operating the shaft 60 and releasing the pawl from engagement therewith.

5. In a device of the class described, a shaft, a window sash, a rack carried by said window sash and engaging said shaft, whereby the sash is operated by said shaft, a pawl, a gear carried by said shaft with which said pawl is normally engaged to prevent movement of the shaft, and an operating cable associated with said pawl for releasing the 70 same from engagement with said shaft.

6. In a device of the class described, a shaft, a window sash, a rack carried by said window sash and engaging said shaft, whereby the sash is operated by said shaft, a pawl, 75 a gear carried by said shaft with which said pawl is normally engaged to prevent movement of the shaft, a drum also carried by said shaft, and an operating cable wound upon said drum and associated with said 80 pawl for operating the shaft and releasing the pawl from engagement therewith.

7. In a device of the class described, a shaft, a window sash, a rack carried by said window sash and engaging said shaft, whereby the sash is operated by said shaft, a spring-actuated pawl, a gear carried by said shaft with which said pawl is normally engaged to prevent movement of the shaft, a drum also carried by said shaft, and an operating cable wound upon said drum and associated with said pawl for operating the shaft and releasing the pawl from engagement therewith.

8. In a device of the class described, a shaft, a window sash connected to said shaft for operation thereby, a drum associated with said shaft, an operating cable wound upon said drum for operating said shaft, a pawl with locking means to prevent movement of 100 said shaft, and means for manually releasing said pawl from engagement with said shaft.

9. In a device of the class described, a shaft, a window sash connected to said shaft for operation thereby, a drum associated 105 with said shaft, an operating cable wound upon said drum for operating said shaft, a pawl with locking means to prevent movement of said shaft, and a rod associated with said pawl for manually releasing the pawl 110 from engagement with said shaft.

In testimony whereof I have hereunto affixed my signature in presence of two witnesses.

IVER JOHNSON.
